UNITED STATES PATENT OFFICE.

HAROLD R. CLIFFORD, OF ROCKFORD, ILLINOIS.

DESIGN FOR A RADIATOR-CAP.

58,286.

Specification for Design.

Patented July 5, 1921.

Application filed February 26, 1921. Serial No. 448,248. Term of patent 3½ years.

To all whom it may concern:

Be it known that I, HAROLD R. CLIFFORD, a citizen of the United States, residing at Rockford, in the county of Winnebago and State of Illinois, have invented a new, original, and ornamental Design for a Radiator-Cap, of which the following is a specification, reference being had to the accompanying drawing, forming part thereof.

In the drawing,—

Figure 1 is a top view of a radiator cap showing my new design; and

Figs. 2, 3 and 4 are front, bottom and end views respectively of said design.

I claim:

The ornamental design for a radiator cap, as shown.

HAROLD R. CLIFFORD.
